The present invention relates to an LED luminaire driving circuit with high power factor, comprising: a filter unit, a rectifier unit, a transformer unit, a power switch unit, a zero current detecting unit, a feedback unit, an error amplifier unit, and a power switch driving unit. Particularly, the LED luminaire driving circuit proposed by the present invention does not include any optocoupler feedback circuits, so it is able to effectively reduce the entire circuit manufacturing cost of this LED luminaire driving circuit. Moreover, this LED luminaire driving circuit can selectively work under CCM operation or DCM operation with high power factor (PF~1), and provide stable output voltage signal and output current signal to load end. In addition, this LED luminaire driving circuit performs excellent stability and current modulation error rate ($<\pm 3\%$).

ABSTRACT

invention relates to an LED luminaire driving high power factor, comprising: a filter unit, a transformer unit, a power switch unit, a zeroing unit, a feedback unit, an error amplifier unit, a switch driving unit. Particularly, the LED luminaire circuit proposed by the present invention does not use optocoupler feedback circuits, so it is able to reduce the entire circuit manufacturing cost of this driving circuit. Moreover, this LED luminaire can selectively work under CCM operation or DCM with high power factor (PF~1), and provide voltage signal and output current signal to load. In this LED luminaire driving circuit performs low voltage and current modulation error rate (<±3%).

LED LUMINAIRE DRIVING CIRCUIT WITH HIGH POWER FACTOR

BACKGROUND OF THE INVENTION

1. Field of the Invention

The present invention relates to the technology fields of LED luminaire driving circuits, and more particularly to an LED luminaire driving circuit with high power factor.

2. Description of the Prior Art

Recently, light-emitting diodes (LEDs) are widely applied to be the lighting device in human life. And currently, more and more families replace the traditional fluorescent lamps by LED lamps due to the issue of Energy Conservation and Carbon Reduction is more and more popular. However, since the power formation of the market electricity is AC power and the LED lamps are driven to emit light by DC power, it is necessary to dispose a power converting device between the market electricity and the LED lamps for converting the AC power to DC power.

With reference to FIG. 1, there is shown a circuit framework diagram of a BCM flyback converter with variable frequency control. The BCM (Boundary Conduction Mode) flyback converter with variable frequency control 1a shown by FIG. 1 is a peak-current-mode PWM (pulse width modulation) converter, and the engineers skilled in LED lamp driving circuit field are able to find the following drawbacks of the BCM flyback converter with variable frequency control 1a from the circuit framework of FIG. 1: (1) the voltage-sensing circuit 11a disposed at the input end of the BCM flyback converter with variable frequency control 1a would produce extra power consumption; and (2) the cut-off time of the secondary side current I_{D_a} of the BCM flyback converter with variable frequency control 1a is fully decided by the output diode D_{O_a} , such that the cut-off time of the secondary side current I_{D_a} cannot be precisely predicted and controlled.

Please refer to FIG. 2, there is shown the circuit framework diagram of another BCM flyback converter with variable frequency control. The BCM (Boundary Conduction Mode) flyback converter with variable frequency control 1b shown by FIG. 2 is a constant on-time control converter, and the engineers skilled in LED lamp driving circuit field can find the following drawbacks of the BCM flyback converter with variable frequency control 1b from the circuit framework of FIG. 2: the cut-off time of the secondary side current I_{D_b} of the BCM flyback converter with variable frequency control 1b is fully decided by the output diode D_{O_b} , so the cut-off time of the secondary side current I_{D_b} cannot be precisely predicted and controlled.

Referring to FIG. 3, which illustrates the circuit framework diagram of a DCM flyback converter with constant frequency control. The DCM (Discontinuous Conduction Mode) flyback converter with constant frequency control 1c shown by FIG. 3 is a voltage control converter, and the engineers skilled in LED lamp driving circuit field is able to easily know that the DCM flyback converter with constant frequency control 1c can merely be used for driving low power LED lamps because the DCM flyback converter with constant frequency control 1c includes higher switching current I_{Q_c} under the same working power.

With reference to FIG. 4, there is shown the circuit framework diagram of a COT flyback converter with variable frequency control. The COT (Constant Off-Time) flyback converter with variable frequency control 1d shown by FIG. 4 is a peak-current-mode PWM (pulse width modulation) converter, and the engineers skilled in LED lamp driving circuit

field are able to find that the COT flyback converter with variable frequency control 1d can be operated under discontinuous conduction mode, boundary conduction mode or continuous conduction mode (CCM); however, the COT flyback converter with variable frequency control 1d still includes the following drawbacks: the voltage-sensing circuit 11d disposed at the input end of the COT flyback converter with variable frequency control 1d would produce extra power consumption.

10 Please refer to FIG. 5, which illustrates the circuit framework diagram of a constant-frequency control flyback converter. The constant-frequency control flyback converter 1e shown by FIG. 5 is a current-clamp control converter, and the engineers skilled in LED lamp driving circuit field can easily understand that the constant-frequency control flyback converter 1e carries out the power factor correction by using the constant current (CC) error amplifier 11e, the constant voltage (CV) error amplifier 12e, the opticalcoupler feedback circuit 13e, the triangle compensation signal V_{tri} , and the 15 power device driving circuit 14e to produce a PWM driving signal to the power transistor Q_{PW} . In spite of that, the constant-frequency control flyback converter 1e still includes the following drawbacks: the entire manufacturing cost of the constant-frequency control flyback converter 1e is too expensive because the disposing of the opticalcoupler feedback circuit 13e.

20 Accordingly, in view of the conventional LED lamps driving circuits all include drawbacks and shortcomings, the inventor of the present application has made great efforts to 30 make inventive research thereon and eventually provided an LED luminaire driving circuit with high power factor.

SUMMARY OF THE INVENTION

35 The primary objective of the present invention is to provide an LED luminaire driving circuit with high power factor, which especially integrated with a zero current detecting unit, a feedback unit and an error amplifier unit without using any input-end voltage detecting signal. The LED luminaire driving circuit can be used for driving high power LED lamps, and work without producing any extra power consumption.

40 The another objective of the present invention is to provide an LED luminaire driving circuit with high power factor, which integrated with a zero current detecting unit, a feedback unit and an error amplifier unit. Particularly, the LED luminaire driving circuit proposed by the present invention does not include any optocoupler feedback circuits, so it is able to effectively reduce the entire circuit manufacturing cost of this LED luminaire driving circuit. Moreover, this 45 LED luminaire driving circuit can selectively work under CCM operation or DCM operation with high power factor (PF~1), and provide stable output voltage signal and output current signal to load end. In addition, this LED luminaire driving circuit performs excellent stability and current modulation error rate (<+3%).

50 Accordingly, to achieve the primary objective of the present invention, the inventor of the present invention provides an LED luminaire driving circuit with high power factor, comprising:

55 a filter unit, coupled to an input source for receiving an AC signal;
a rectifier unit, coupled to the filter unit for receiving the AC signal via the filter unit, and then treats the AC signal with a rectifying process so as to output an input signal;
60 a transformer unit, coupled to the rectifier unit for receiving the input signal, and then transforms the input signal having a peak input voltage to an output signal having a peak output

voltage, so as to output the output signal to an LED lighting unit for making the LED lighting unit emit light;

a power switch unit, coupled between the rectifier unit and the transformer unit and used for treating the input signal with switching control;

a zero current detecting unit, being coupled to the transformer unit and used for treating the output signal with a zero current detection, so as to output a zero current detection signal;

a feedback unit, being coupled to the zero current detecting unit and the power switch unit, wherein the feedback unit receives a power switch current and the zero current detection signal, and outputting a feedback signal according to the power switch current and the zero current detection signal;

an error amplifier unit, being coupled to the zero current detecting unit and the feedback unit for receiving the feedback signal, and then outputs an error amplification signal according to the feedback signal; and

a power switch driving unit, being coupled to the power switch unit and the error amplifier unit for receiving the error amplification signal, and then outputs a driving signal to the power switch unit according to the error amplification signal, so as to drive the power switch unit to treat the input signal with switching control.

BRIEF DESCRIPTION OF THE DRAWINGS

The invention as well as a preferred mode of use and advantages thereof will be best understood by referring to the following detailed description of an illustrative embodiment in conjunction with the accompanying drawings, wherein:

FIG. 1 is a circuit framework diagram of a BCM flyback converter with variable frequency control;

FIG. 2 is a circuit framework diagram of another BCM flyback converter with variable frequency control;

FIG. 3 is a circuit framework diagram of a DCM flyback converter with constant frequency control;

FIG. 4 is a circuit framework diagram of a COT flyback converter with variable frequency control;

FIG. 5 is a circuit framework diagram of a constant-frequency control flyback converter;

FIG. 6 is a circuit block diagram of an LED luminaire driving circuit with high power factor according to the present invention;

FIG. 7 is a circuit framework diagram of the LED luminaire driving circuit with high power factor according to the present invention;

FIG. 8 shows signal waveforms of the LED luminaire driving circuit working under DCM operation;

FIG. 9 is a plot of an input current as a function of the conduction angle;

FIG. 10 shows signal waveforms of the LED luminaire driving circuit working under CCM operation;

FIG. 11 shows curves of the input current and the conduction angle;

FIG. 12 is a plot of the input current as a function of the conduction angle;

FIG. 13A and FIG. 13B show simulated signal waveforms of the LED luminaire driving circuit working under CCM operation; and

FIG. 14A and FIG. 14B show simulated signal waveforms of the LED luminaire driving circuit working under DCM operation.

DETAILED DESCRIPTION OF THE PREFERRED EMBODIMENTS

To more clearly describe an LED luminaire driving circuit with high power factor according to the present invention,

embodiments of the present invention will be described in detail with reference to the attached drawings hereinafter.

With reference to FIG. 6, there is shown a circuit block diagram of an LED luminaire driving circuit with high power factor according to the present invention. As shown in FIG. 6, the LED luminaire driving circuit 1 of the present invention includes: a filter unit 10, a rectifier unit 11, a transformer unit 12, an output unit 13, a power switch unit 15, a zero current detecting unit 16, a feedback unit 17, an error amplifier unit 18, and a power switch driving unit 19.

Referring to FIG. 6 again, and please simultaneously refer to FIG. 7, which shows a circuit framework diagram of the LED luminaire driving circuit with high power factor. As shown in FIG. 6 and FIG. 7, the filter unit 10 is coupled to an input source V_s for receiving an AC signal. The filter unit 10 consists of a first capacitor C_{x1} , a common mode chock winding L_{CM} and a second capacitor C_{x2} , wherein the first capacitor C_{x1} is connected across the two input terminals of the common mode chock winding L_{CM} , and the second capacitor C_{x2} is connected across the two output terminals of the common mode chock winding L_{CM} . The rectifier unit 11 is a bridge rectifier, which is coupled to the filter unit 10 for receiving the AC signal via the filter unit 10, and then treats the AC signal with a rectifying process so as to output an input signal V_{in} .

The transformer unit 12 is coupled to the rectifier unit 11 and has a primary winding coil N_p , a secondary winding coil N_s and an auxiliary winding coil N_a . In the present invention, the transformer unit 12 is used for receiving the input signal V_{in} , and then transforming the input signal V_{in} having a peak input voltage to an output signal V_o having a peak output voltage, so as to output the output signal V_o to an LED lighting unit 14 for making the LED lighting unit 14 emit light.

Inheriting to above description, the output unit 13 is coupled between the transformer unit 12 and the LED lighting unit 14 for outputting the output signal V_o to the LED lighting unit 14. As shown in FIG. 7, the output unit 13 is consisted of an output diode D_o and an output capacitor C_o , wherein the output diode D_o is coupled to the one terminal of the primary winding coil N_p by one end thereof, and the output capacitor C_o is coupled to the other end of the output diode D_o by one end thereof, moreover the other end of the output capacitor C_o is coupled to other terminal of the primary winding coil N_p and the LED lighting unit 14.

The power switch unit 15 is a Power Metal-Oxide-Semiconductor Field-Effect Transistor (power MOSFET), and the source terminal of the power MOSFET Q is coupled with a source resistor R_s . The power switch unit 15 is coupled between the rectifier unit 11 and the transformer unit 12 and used for treating the input signal V_{in} with switching control. Particularly, the LED luminaire driving circuit 1 of the present invention includes a zero current detecting unit 16, which is able to detect the output signal V_o via a signal detecting unit 16a coupled between the transformer unit 12 and the zero current detecting unit 16. As shown in FIG. 6 and FIG. 7, the signal detecting unit 16a has at least one resistor (R_{dect1}, R_{dect2}), wherein one end of the resistor (R_{dect1}, R_{dect2}) is coupled to one terminal of the auxiliary winding coil N_a , and the other end of the resistor is coupled to the other terminal of the auxiliary winding coil N_a and the ground of the LED luminaire driving circuit 1. Thus, the zero current detecting unit 16 is able to output a zero current detection signal Z_{CD} after receiving a detection signal V_{det} from the signal detecting unit 16a.

The zero current detecting unit 16 consists of a comparator 161, an adder 162, an inverter 163, and a Set/Reset flip flop

164, wherein the comparator 161 is coupled to the signal detecting unit 16a for receiving the detection signal V_{dec} . The adder 162 is coupled between a first input end and an output end of the comparator 161, moreover the adder 162 is further coupled with a reference signal V_{REF1} . Besides, the inverter 163 is coupled to the output end of the comparator 161, and the Set/Reset flip flop 164 is respectively coupled to the inverter 163 and the power switch unit 15 by one reset end and one set end thereof.

Inheriting to above description, the feedback unit 17 is coupled to the zero current detecting unit 16 and the power switch unit 15. In the present invention, the feedback unit 17 is used for receiving a power switch current I_Q of the power switch unit 15 and the zero current detection signal Z_{CD} , and then outputting a feedback signal V_{FB} according to the power switch current I_Q and the zero current detection signal Z_{CD} . As shown in FIG. 6 and FIG. 7, the feedback unit 17 includes a low pass filter 171 and a multiplexer 172, wherein the low pass filter 171 is coupled to power switch unit 15 for receiving the power switch current I_Q , so as to treat the power switch current I_Q with a low pass filtering process. The multiplexer 172 is coupled to the low pass filter 171 and the zero current detecting unit 16 for receiving the zero current detection signal Z_{CD} and the low-pass-filtered power switch current I_Q , so as to output the feedback signal V_{FB} . Moreover, the feedback unit 17 further includes a relay coupled between the multiplexer 172 and the error amplifier unit 18.

The error amplifier unit 18 is coupled to the zero current detecting unit 16 and the feedback unit 17 for receiving the feedback signal V_{FB} , and then outputs an error amplification signal V_{ea} according to the feedback signal V_{FB} . In addition, the power switch driving unit 19 is coupled to the power switch unit 15 and the error amplifier unit 18 for receiving the error amplification signal V_{ea} , so as to output a driving signal V_G to the power switch unit 15 according to the error amplification signal V_{ea} ; therefore, the power switch unit 15 is able to treat the input signal Vin with switching control according to the driving signal V_G .

As shown in FIG. 6 and FIG. 7, the error amplifier unit 18 consists of a proportional-integral (PI) compensator 181 and a multiplexer 182, wherein the PI compensator 181 is coupled to the feedback unit 17 for receiving the feedback signal V_{FB} , and the multiplexer 182 is coupled to the power switch driving unit 19 for receiving the driving signal V_G . Moreover, the multiplexer 182 is further coupled with a reference current signal I_{REF} , such that the multiplexer 182 is able to output a reference voltage signal V_{REF} to the PI compensator 181 according to the driving signal V_G and the reference current signal I_{REF} , and then the PI compensator 181 may output the error amplification signal V_{ea} to a subtractor 191 of the power switch driving unit 19 according to the reference voltage signal V_{REF} and the feedback signal V_{FB} .

Besides the error amplification signal V_{ea} , the subtractor 191 coupled to the error amplifier unit 18 simultaneously receiving the a ripple signal V_{rip} , therefore the subtractor 191 outputs a conversion signal V_{con} to a comparator 192 of the power switch driving unit 19 according to the ripple signal V_{rip} and the error amplification signal V_{ea} . The comparator 192, coupled to the subtractor 191 and the power switch unit 15, is used for respectively receiving the conversion signal V_{con} and a power switch voltage signal V_{CS} of the power switch unit 15; therefore, the comparator 192 would output a comparison signal according to the power switch voltage signal V_{CS} and the conversion signal V_{con} . As shown in FIG. 6 and FIG. 7, the power switch driving unit 19 further includes a Set/Reset flip flop 193, which is coupled to the output end of the comparator 193 by one reset end thereof; moreover, one

set end of the Set/Reset flip flop 193 is coupled with a clock signal CLK, such that the Set/Reset flip flop 193 is able to output the driving signal V_G to the power switch unit 15 according to the clock signal CLK and the comparison signal received from the comparator 193.

Therefore, above descriptions have been introduce the detailed circuit framework of the LED luminaire driving circuit 1 proposed by the present invention; Next, in order to prove the practicability and performance of the LED luminaire driving circuit 1, a variety of circuit simulation are completed and the related simulation data are recorded. Please refer to FIG. 8, which shows signal waveforms of the LED luminaire driving circuit working under DCM (Discontinuous Conduction Mode) operation. From the signal waveforms, it is able to derive the following formula (1): $V_{con}=V_{ea}-m_a T_{on}=m_1 T_{on}$. In above-mentioned formula (1), V_{con} is the conversion signal outputted by the subtractor 191 of the power switch driving unit 19, V_{ea} is the error amplification signal V_{ea} outputted by the PI compensator 181 of the error amplifier unit 18, and T_{on} is the conduction time of the power switch unit 15, m_a is the slope of the ripple signal V_{rip} , and m_1 is the slope of the ripple signal V_{CS} of the power MOSFET Q of the power switch unit 15. Moreover, the I_D marked in FIG. 8 means the diode current of the output diode D_O of the output unit 13.

Since $m_1=(R_S * V_S)/L_p$ and $I_{pk}=(T_{on} * m_1)/R_S$, the T_{on} can be calculated by the formula of $T_{on}=V_{ea}/(m_1+m_a)$. Herein L_p means the self-inductance of the transformer unit 12 and I_{pk} means the peak value of the power switch current I_Q . Moreover, because input current I_S is equal to the average value of the power switch current I_Q in a switching period, the input current I_S can be calculated by using the formula of $I_S=(I_{pk} * T_{on})/2T_S$; wherein T_S is the switching period of the power MOSFET Q of the power switch unit 15. Subsequently, it is able to derive the following formula (2): $I_S=(V_{ea}^2/2R_S T_S) * [m_1/(m_1+m_a)]^2$. Eventually, after letting $m_a=K_S M_{1,max}=K_S R_S (V_{sm}/L_p)$ and substituting different slope compensating parameter K_S and slope m_a into above-mentioned formula (2), a plot of the input current I_S as a function of the conduction angle can be obtained and shown as FIG. 9. From the plot of FIG. 9, it is able to observe that the greater value the slope compensating parameter K_S is set, the less distortion the input current I_S shows.

Continuously referring to FIG. 10, which shows signal waveforms of the LED luminaire driving circuit working under CCM (continuous conduction mode) operation. From FIG. 10, it is able to derive the following formula (3): $\Delta I_{pk}=(m_1 * T_{on})/R_S$. Because input current I_S is equal to the average value of the power switch current I_Q in a switching period, the input current I_S can be calculated by using the following formula (4): $I_S=I_a(T_{on}/T_S)+(\Delta I_{pk} T_{on})/2T_S$, wherein the LED luminaire circuit 1 of the present invention would work under DCM operation when $I_a < I_{pk}$. Moreover, as FIG. 11 shows, when the conduction angle is ranged between θ_0 and $\pi-\theta_0$ and different slope compensating parameter K_S is substituted into above-mentioned formula (4), a plot of the input current I_S as a function of the conduction angle can be obtained and shown as FIG. 12. From the plot of FIG. 12, it is able to observe that the greater value the slope compensating parameter K_S is set, the less distortion the input current I_S shows.

Please refer to FIG. 13A and FIG. 13B, there are shown simulated signal waveforms of the LED luminaire driving circuit working under CCM operation. The simulated signal waveforms shown by FIG. 13A and FIG. 13B have been proved that the LED luminaire driving circuit 1 proposed by the present invention can provide stable output voltage signal V_O and output current signal I_O , and simultaneously performs

excellent stability and current modulation error rate ($<\pm 3\%$). In addition, from FIG. 13A, it can find that the power factor (PF) of the LED luminaire driving circuit 1 working under CCM operation (i.e., $V_S=110V_{rms}$) reaches to 0.991, and the working current I_{LED} of the LED lighting unit 14 oppositely reaches to 519 mA.

Moreover, please refer to FIG. 14A and FIG. 14B, there are shown simulated signal waveforms of the LED luminaire driving circuit working under DCM operation. The simulated signal waveforms shown by FIG. 14A and FIG. 14B have been proved that the LED luminaire driving circuit 1 proposed by the present invention can provide stable output voltage signal V_O and output current signal I_O , and simultaneously performs excellent stability and current modulation error rate ($<\pm 3\%$). In addition, from FIG. 14A, it can find that the power factor (PF) of the LED luminaire driving circuit 1 working under DCM operation (i.e., $V_S=220V_{rms}$) reaches to 0.953, and the working current I_{LED} of the LED lighting unit 14 oppositely reaches to 501 mA. Therefore, the simulated signal waveforms of FIG. 13A, FIG. 13B, FIG. 14A, and FIG. 14B proves that the LED luminaire driving circuit 1 proposed by the present invention can indeed works under different mode (CDM or DCM) operation with high power factor.

The above description is made on embodiments of the present invention. However, the embodiments are not intended to limit scope of the present invention, and all equivalent implementations or alterations within the spirit of the present invention still fall within the scope of the present invention.

What is claimed is:

1. An LED luminaire driving circuit with high power factor, comprising:
  - a filter unit, being coupled to an input source for receiving an AC signal;
  - a rectifier unit, being coupled to the filter unit for receiving the AC signal via the filter unit, and then treats the AC signal with a rectifying process so as to output an input signal;
  - a transformer unit, being coupled to the rectifier unit for receiving the input signal, and transforming the input signal having a peak input voltage to an output signal having a peak output voltage, so as to output the output signal to an LED lighting unit for making the LED lighting unit emit light;
  - a power switch unit, being coupled between the rectifier unit and the transformer unit and used for treating the input signal with switching control;
  - a zero current detecting unit, being coupled to the transformer unit and used for treating the output signal with a zero current detection, so as to output a zero current detection signal;
  - a feedback unit, being coupled to the zero current detecting unit and the power switch unit, wherein the feedback unit receives a power switch current of the power switch unit and the zero current detection signal, and outputting a feedback signal according to the power switch current and the zero current detection signal; wherein the feedback unit comprises:
    - a low pass filter, being coupled to power switch unit for receiving the power switch current, so as to treat the power switch current with a low pass filtering process; and
    - a multiplexer, being coupled to the low pass filter and the zero current detecting unit for receiving the zero current detection signal and the low-pass-filtered power switch current, so as to output the feedback signal;

an error amplifier unit, being coupled to the zero current detecting unit and the feedback unit for receiving the feedback signal, and then outputs an error amplification signal according to the feedback signal; and a power switch driving unit, being coupled to the power switch unit and the error amplifier unit for receiving the error amplification signal, and then outputs a driving signal to the power switch unit according to the error amplification signal, so as to drive the power switch unit to treat the input signal with switching control.

2. The LED luminaire driving circuit with high power factor of claim 1, wherein the power switch unit comprises a Power Metal-Oxide-Semiconductor Field-Effect Transistor (power MOSFET), and the source terminal of the power MOSFET being coupled with a source resistor.

3. The LED luminaire driving circuit with high power factor of claim 1, wherein filter unit comprises a first capacitor, a common mode chock winding and a second capacitor, in which the first capacitor is connected across the two input terminals of the common mode chock winding, and the second capacitor being connected across the two output terminals of the common mode chock winding.

4. The LED luminaire driving circuit with high power factor of claim 1, wherein the rectifier unit is a bridge rectifier.

5. The LED luminaire driving circuit with high power factor of claim 1, wherein the feedback unit further comprises a relay coupled between the multiplexer and the error amplifier unit.

6. The LED luminaire driving circuit with high power factor of claim 1, wherein the error amplifier unit comprises: a proportional-integral (PI) compensator, being coupled to the feedback unit for receiving the feedback signal; and a multiplexer, being coupled to the power switch driving unit for receiving the driving signal, moreover the multiplexer further be coupled with a reference current signal, such that the multiplexer is able to output a reference voltage signal to the PI compensator according to the driving signal and the reference current signal, and then the PI compensator may output the error amplification signal according to the reference voltage signal and the feedback signal.

7. The LED luminaire driving circuit with high power factor of claim 1, wherein the power switch driving unit comprises:

a subtractor, being coupled to the error amplifier unit for receiving the error amplification signal, moreover the subtractor further be coupled with a ripple signal, such that the subtractor is able to output a conversion signal according to the ripple signal and the error amplification signal;

a comparator, being coupled to the subtractor and the power switch unit for receiving the conversion signal and a power switch voltage signal of the power switch unit, respectively; therefore the comparator may output a comparison signal according to the power switch voltage signal and the conversion signal; and

a Set/Reset flip flop, being coupled to the output end of the comparator by one reset end thereof, moreover one set end of the Set/Reset flip flop is coupled with a clock signal, such that the Set/Reset flip flop is able to output the driving signal to the power switch unit according the clock signal and the comparison signal received from the comparator.

8. The LED luminaire driving circuit with high power factor of claim 1, further comprising: an output unit, being coupled between the transformer unit and the LED lighting

unit, wherein the output unit is used for outputting the output signal to the LED lighting unit for making the LED lighting unit emit light.

9. The LED luminaire driving circuit with high power factor of claim 8, further comprising: a signal detecting unit, being coupled between the transformer unit and the zero current detecting unit, wherein the signal detecting unit is used for detecting the output signal, so as to output a detection signal to the zero current detecting unit.

10. The LED luminaire driving circuit with high power factor of claim 9, wherein the zero current detecting unit comprises:

a comparator, being coupled to the signal detecting unit for receiving the detection signal, and having a first input end, a second input end and an output end;
 an adder, being coupled between the first input end and the output end of the comparator, and the adder further being coupled with a reference signal;
 an inverter, being coupled to the output end of the comparator; and
 a Set/Reset flip flop, being respectively coupled to the inverter and the power switch unit by one reset end and one set end thereof.

11. The LED luminaire driving circuit with high power factor of claim 9, wherein the transformer unit has a primary winding coil, a secondary winding coil and an auxiliary winding coil.

12. The LED luminaire driving circuit with high power factor of claim 11, wherein the output unit comprises:

an output diode, being coupled to the one terminal of the primary winding coil by one end thereof; and
 an output capacitor, being coupled to the other end of the output diode by one end thereof, moreover the other end of the output capacitor is coupled to other terminal of the primary winding coil and the LED lighting unit.

13. The LED luminaire driving circuit with high power factor of claim 11, wherein the signal detecting unit has at least one resistor, in which one end of the resistor is coupled to one terminal of the auxiliary winding coil, and the other end of the resistor being coupled to the other terminal of the auxiliary winding coil and the ground of the LED luminaire driving circuit with high power factor.
